COMBINATION COUPLER AND HANGER
STRUCTURE FOR SCREW CONVEYERS

Joseph L. Kozak, Munster, Ind., and Clarence F. Abraham, Chicago, Ill., assignors to Screw Conveyor Corporation, Hammond, Ind., a corporation of Illinois

Application September 25, 1940, Serial No. 358,228

17 Claims. (Cl. 198—213)

The present invention relates to conveyer apparatus of the screw or spiral conveyer type, and particularly to apparatus of this character which is made up in lengths requiring a plurality of units or sections, and hence necessitating coupling means between both the casing or housing sections and also the sections of the screw or spiral conveyer mechanism inside said casing or housing sections.

Since the conveyer apparatus requires hanger structures to provide bearing means for the conveyer mechanism at spaced intervals within the conveyer housing or casing, a primary purpose of the present invention is to provide an improved construction whereby such bearing means may be located at the same points where the coupling means between the housing or casing sections are located.

For carrying out this purpose of our invention we have devised a combination form of coupling and hanger unit to afford the necessary coupling means between adjoining sections of the housing or casing of the conveyer apparatus, and also incorporate therewith a hanger structure for providing suitable bearing means for the coupling between corresponding sections of the conveyer mechanism—all with a view to enabling sections of the casing or housing to be repaired or replaced without disturbing the conveyer mechanism or its bearings, and furthermore to enable sections of the conveyer mechanism also to be similarly repaired or replaced without undue disturbance of the adjoining casing or housing units of the apparatus.

Incidentally it is proposed, by such new arrangement and connections, to provide a much more stable and rigidly braced hanger and bearing construction, adapted to maintain a more accurate alignment of the bearings, as well as higher operating efficiency of the conveyer mechanism.

It is further sought to design and adapt the essential features of the aforesaid improvements for use with any of the well-known types or forms of casings or housings forming the conveyer trough—such as cylindrical, U- or V-shaped, square, rectangular, flaring, or other forms, and including either integral or sectional casing or housing units, as will be fully explained in the following.

Having these general objects in view, the invention will accordingly be described by reference to the accompanying drawings, illustrating suitable forms of apparatus designed to embody the proposed improvements, after which those features and combinations which are deemed to

be both novel and patentable will be particularly set forth and claimed.

In the drawings—

Figure 1 is an elevation illustrating a conveyer apparatus constructed in accordance with the present invention and comprising horizontally split conveyer trough or casing units or sections;

Figure 2 is a transverse sectional view on a larger scale and illustrating a section taken on the line 2—2 of Figure 1;

Figure 3 is an elevation representing a section taken on the line 3—3 of Figure 2;

Figure 4 is a similar view representing a section taken on the line 4—4 of Figure 3;

Figure 5 is a side elevation of one of the combination hanger and coupling units of the construction;

Figure 6 is a transverse sectional view, representing a section taken on the line 6—6 of Figure 5;

Figure 7 is a perspective view of the upper portion of the hanger and coupling assembly and bearing parts;

Figure 8 is a similar view showing the lower portion of said assembly;

Figure 9 is a sectional detail of the joint between conveyer trough sections and represents a section taken on the line 9—9 of Figure 1—but on a larger scale.

Figure 10 is an elevation showing a modified form of construction—being a section taken on the line 10—10 of Figure 11;

Figure 11 is a vertical sectional view, representing a section taken on the line 11—11 of Figure 10;

Figure 12 is an elevation similar to Figure 10 but showing another modified form of construction;

Figure 13 is a fragmentary side view of the same, with the hanger structure shown in vertical section;

Figure 14 is an elevation similar to Figure 10 but illustrating another modification;

Figure 15 is a fragmentary side view of the same but partly in section along the line 15—15 of Figure 14;

Figure 16 is a fragmentary elevation showing another modification;

Figure 17 is a transverse sectional view of the same;

Figure 18 is a fragmentary elevation showing still another modification;

Figure 19 is a transverse sectional view of the same taken on the line 19—19 of Figure 18;

Figure 20 is a fragmentary elevation of a further modification;

Figure 21 is a transverse sectional view of the same, being a section taken on the line 21—21 of Figure 20;

Figure 22 is a sectional detail view, representing a section taken on the line 22—22 of Figure 1, but on a larger scale;

Figure 23 is an elevation (similar to Figure 1) illustrating conveyer apparatus comprising unitary cylindrical casing or trough sections and making use of a further modified form of hanger and coupling units between the different sections or trough units of the apparatus;

Figure 24 is a transverse sectional view, representing a section taken on the line 24—24 of Figure 23, but on a larger scale;

Figure 25 is an elevation representing a section taken on the line 25—25 of Figure 24;

Figure 26 is a view similar to Figure 25, but showing a modified position of the hanger structure proper;

Figure 27 is an elevation similar to Figure 24 but illustrating a still further modified form of hanger and coupling unit and representing a section taken on the line 27—27 of Figure 28;

Figure 28 is a vertical sectional view, illustrating a section taken on the line 28—28 of Figure 27;

Figure 29 is an elevation (similar to Figure 1) illustrating a conveyer apparatus comprising U-shaped trough sections and utilizing correspondingly modified forms of hanger and coupling units between the trough units or sections of the conveyer;

Figure 30 is a transverse sectional view, on a larger scale and representing a section taken on the line 30—30 of Figure 29;

Figure 31 is a sectional elevation, representing a section taken on the line 31—31 of Figure 30;

Figure 32 is a perspective view showing the hanger structure represented in Figures 30 and 31;

Figure 33 is a sectional elevation similar to Figure 31 but illustrating a modified form of the hanger and coupling construction;

Figure 34 is an elevation of the hanger and coupling unit shown in Figure 33; and

Figure 35 is an enlarged detail sectional view of the joint structure between the trough and cover shown in Figure 30.

Conveyer apparatus of the type herein involved is commonly of such a length as to require the same to be made up in several longitudinal sections, having couplings between the conveyer trough or housing sections and also between the successive sections of spiral or screw conveyer inside the trough or housing sections. These conveyer sections require bearing or hanger assemblies inside the trough or housing and the practice has usually been to stagger the joints between the trough sections with reference to the couplings between conveyer sections, because of no provision being made for accommodating or combining the trough couplings and the conveyer hangers and bearings in a single assembly or unit. One of the principal objections to such a practice is the fact that the hanger and bearing structure is not afforded a sufficiently rigid support by merely anchoring it to the sheet metal of the trough; that is, at some distance from the joints between the trough sections which are of course somewhat stronger on account of the re-

inforcement produced by the connecting means; and where the trough is of the closed type, such practice is also objectionable on account of rendering it more difficult to make ready or efficient inspection and repair operations.

Where, as in the present improved construction, the purpose of the invention is to design the apparatus so as to locate the joints between the trough sections and the conveyer sections at corresponding points along the apparatus, the result of such a design is to combine the coupling and hanger or bearing parts into unitary assemblies or units adapted not only to promote the highest efficiency as regards the coupling, bearing and alining functions with respect to the successive sections of both the trough and conveyer parts of the apparatus, but also to provide maximum benefits or advantages as regards greater operating efficiency of the entire apparatus as well as the carrying out of the maintenance operations of inspection and repair of the apparatus, as often as may be necessary.

The improved construction, being particularly well adapted to closed types of conveyer apparatus, the invention is accordingly described and illustrated as applied to such types—although it is to be understood that our invention is not limited to such specific applications.

Referring now to the accompanying drawings in detail, and more particularly in the first instance to Figures 1 to 8, the improved hanger and coupling construction is illustrated as part of a spiral conveyer apparatus utilizing a round or cylindrical trough or casing for the flow or movement of the material as it is impelled by the spiral or screw conveyer mechanism. Figure 1 shows said apparatus in a complete assembly made up of three sections or matched units joined together by the present improved hanger and coupling construction—the only difference between said sections or units being the provision of an intake or feed structure 50 and an outlet member 51 at the opposite ends of the apparatus. The apparatus further includes end bearing units 52 and 53 for the opposite ends of the conveyer, which is designed to be driven by a countershaft drive unit 54 connected with the bearing unit 52. The present invention is concerned primarily with the novel type of construction for connecting adjoining ends of the aforesaid sections or matched units of the conveyer and trough or casing, and comprising assemblies which include a hanger structure for journaling the connections between the screw conveyer sections, as illustrated in more detail in Figures 2 to 8.

The conveyer casing or trough is shown as of round or cylindrical design (though the invention is not confined to any particular cross-sectional design), and preferably the trough units are split horizontally, forming top and bottom housing sections 55, having outwardly projecting flanges 56 which are secured together by suitable bolts 57, and preferably also enclosed by channel strips 58, thus producing an effective dust seal (see Figure 9).

The opposite ends of the conveyer trough or casing sections 55 are also formed with outwardly projecting flanges 61 adapted to be secured by means of bolts 62 not only to the end bearing units 52 and 53, but also to the intermediate hanger and coupling units in the manner shown both in Figure 1 and also in Figures 3 and 5.

In the form of construction illustrated in Figures 1 to 8, each of these intermediate hanger

and coupling units is made up of an assembly comprising parts adapted to be separated and knocked down as illustrated in Figures 7 and 8. The main parts of said assembly comprise upper and lower semicircular sections 63 and 64, respectively formed with flanges 65 for bolting to the trough flanges 61 (see Figures 1 and 5), and connecting portions 66 for bolting together by means of bolts 67 (Figs. 5 and 6).

The lower section 64 is formed with a base or foot portion 68 for anchoring purposes (similar to the lower or base portions of the units 52, 53 and 54), while the upper portion 63 of the coupling unit is formed with a radial web portion 71 provided with a half bearing section 72 designed to cooperate with a cap bearing section 73 to complete the hanger-bearing structure for a conveyer shaft coupling 74. These bearing elements 72 and 73 are maintained in mating or cooperative bearing relation by means of a U-bolt 75 fitting a groove 76 in the cap bearing 73 and channels 77 at opposite sides of the web portion 71—the ends of said bolt 75 projecting through openings 78 in the top section 63 for receiving nuts 81, all as clearly shown in Figure 6. A lubricating connection 82 (extending through each web portion 71) is also provided for each of the hanger bearing structures (see Figures 3 and 6).

A conveyer section comprises its ribbon or conveyer flight portion 83 and tubular shaft section 84, the ends of which are adapted to be connected together by a coupling 74 and secured thereto by bolts 85 at the opposite sides of the hanger bearing structure—as illustrated in Figure 3.

For carrying out the purposes of the present invention, each of the units or sections of the apparatus comprises a spiral conveyer section 83 and a conveyer casing or trough section 55 of the same length, as a result of which each hanger and coupling unit matches up the ends between the adjoining sections of the successive units of the apparatus. The primary advantage of this is in connection with replacements or repairs, which are greatly facilitated, due to the method of assembly shown and the standard relationship of the parts comprising the improved structural design. For example, if a hanger bearing has proved defective and requires repair or replacement, the necessary steps require simply the removal of the bolts 62 and 67 which secure the hanger and coupling sections together and to the trough flanges 61, and also the nuts 81, to release the U-bolt 75 supporting the lower cap-bearing section 73. The hanger and coupling assembly can then be manipulated for whatever changes or replacements are necessary, and thereafter reassembled into original operative relation to the conveyer and trough sections.

For the purpose of facilitating such repair or replacement operations, we propose providing the upper trough or casing section 55 with a removable handhole cover section 55' having its ends formed with semicircular flanges 61' for making connection not only with the trough coupling and hanger unit but also with the corresponding casing section 55 by means of the additional securing bolts 62', as illustrated in Figures 1 and 22.

Again, an intermediate section of spiral conveyer 83—84 may be removed for repair or replacement without disturbing the rest of the apparatus except to the extent of removing the hanger and coupling assemblies at the ends of that section (including the coupling bolts 85),

whereupon the shaft couplings 74 may be telescoped into the tubular conveyer shafts 84 far enough to clear the ends of the spiral conveyer section and thus allow the latter to be removed. Thereafter the reassembly is of course carried out by simply reversing the procedure.

Moreover, the conveyer trough sections 55 being split horizontally, such a type of construction is adapted to facilitate easy and convenient access to the interior of the apparatus whenever necessary for inspection or the carrying out of any repair operations with reference to the screw conveyer mechanism itself—or the hanger bearings, conveyer couplings, etc., as may be required.

Various modified forms of construction of the apparatus, all designed for accomplishing the same essential results aimed at by the invention, are illustrated in the remaining views of the drawings.

Referring to Figures 10 and 11, the construction is of a type designed for operation at relatively higher speeds. Accordingly the hanger coupling unit is not split horizontally (as in Figures 1 to 8) but in an oblique direction as clearly shown in Figure 10. The lower portion 91 of the hanger and coupling unit, having the base or supporting part 68', is also formed with an inwardly projecting web or hanger arm 92 carrying one of the bearing elements, 93, for cooperating with a cap bearing element 94 to provide the hanger structure for the shaft coupling 74, said cap bearing having an extension 95 provided with screws 96 for securing the same to the web or arm 94 as shown. The specific split construction and method of supporting the bearing structure is such as to offset the hanger or supporting structure to one side of the vertical plane through the bearing axis and thereby provide ample clearance and minimum obstruction of the material flow, which of course tends to climb up one side of the conveyer housing or trough, depending upon the direction of its longitudinal travel through the apparatus.

In this connection it may be pointed out that the construction is adapted to allow a reversal of the unit between the trough sections according to whether the conveyer is of the right hand or left hand design, so that the bearing supporting structure 92—96 will be located at the proper side of the conveyer trough to correspond with the hand of the conveyer, and hence the direction of the flow or movement of the material.

The modification illustrated in Figures 12 and 13 omits the split feature of the coupler construction above described and utilizes a continuous and approximately ring-shaped hanger and coupling plate 100 having the base or supporting portion 101 and also the series of bolt openings 102 whereby the plate 100 is adapted to be secured by bolts 99 between the flanges 61 of the trough sections as shown in Figure 13. The hanger structure itself comprises a shelf projection 103 carried by the upper portion of the plate 100, to which shelf is secured, by bolts 105, the upper flanged portion of a bearing block 104, the lower portion of which is formed with the upper half or section 106 of the bearing. The lower cap bearing element 107 is removably secured in its bearing relation to the upper section 106 by means of a U-bolt 108, the upper ends of which project through suitable openings in the top portion of said block 104 and the shelf 103 and are retained by means of nuts 109.

Referring to Figures 14 and 15, the modification shown comprises a horizontally split type of hanger and coupling unit having the upper section 112 provided with an interior U-shaped supporting hanger 113 suspended from a pair of bolts 114. Thus the hanger member 113 provides a carrier or saddle for the upper and lower bearing sections 115 and 116, respectively, which are retained in the proper relation by means of a keeper plate 117 which is secured by bolts 118 to the opposite sides of the hanger member 113, as illustrated.

In Figures 16 and 17, the hanger and coupling unit is illustrated as made with a top removable section 121 which is formed with a radial or inwardly projecting hanger arm 122, and this arm is made integral with the upper bearing section 123. The lower half of the bearing is in the form of a removable cap section 124 which is secured by bolts 125 to the upper bearing section 123.

In the modification shown in Figures 18 and 19, the hanger and coupling unit is also provided with an upper removable section 141, and the hanger structure comprises an approximately V-shaped frame 142 for carrying the split bearing sections 143, which are held in mating relation by means of a curved keeper bar 144 embracing the upper bearing section and secured at its ends by bolts 145 to the opposite arms of the V-shaped frame 142. As clearly shown in Figure 18, the opposite ends of the V-shaped frame 142 are removably secured in place by the same bolts 146 which are used to secure the sections of the hanger and coupling unit together.

Figures 20 and 21 show another horizontally split type of hanger and coupling unit, the upper section 151 of which is provided with a split and inwardly projecting hanger structure comprising duplicate sections 152 secured together and to the section 151 by means of bolts 153, as clearly illustrated in Figure 20. The inner free ends of the hanger sections 152 are suitably bowed as indicated at 154 for embracing and securely retaining the split bearing sections 155 in operative assembled relation, as shown. Ridges 155' on the bearing sections also aid in maintaining that relation.

Referring now to Figures 23 to 26, Figure 23 illustrates a conveyer apparatus made up of integral or one-piece cylindrical housing or trough sections 160, and using hanger and coupling units of a design which is illustrated in greater detail in Figures 24 and 25.

These hanger and coupling units are of the vertically split type comprising sections 161 having top and bottom web portions 163 secured together by bolts 162, and also formed with flanges 163 for coupling to the end flanges 164 of the trough sections 160 by means of bolts 165, as illustrated. Each of the sections 161 of each unit is formed with a radial inwardly projecting hanger arm 166 terminating in a half bearing section 167 for embracing the shaft coupling 168 of the conveyer mechanism, as clearly shown in Figures 24 and 25. The bottoms of the sections 161 also unite to form a supporting base or foot member 168.

The form just referred to as illustrated in Figure 25 shows the hanger structure arranged at one side of the hanger and coupling unit; but, the construction may as well be designed to arrange said hanger structure at the opposite side of the unit, or in any desired intermediate position, as illustrated at 166' in Figure 26.

In Figures 27 and 28 is illustrated a fabricated hanger and coupling unit adapted for the type of construction just described, and comprising split cylindrical trough sections 170 (i. e., a sheet-metal construction) having longitudinal flanges 169 for securing the sections together at top and bottom by bolts 171 and also the end flanges 169' for attachment to adjoining trough sections 160 by bolts 172.

The hanger structure comprises radial arms of suitably built-up elements 173 projecting inward from corresponding sections 170 and from diametrically opposite flanged margins thereof, and terminating in half bearing sections 174 for embracing split bearing bushings 175 designed for accommodating the conveyer shaft coupling. The flanged sections 170 are of sufficient extent for lending the necessary strength and rigidity to the hanger unit, as represented in Figure 27. In the construction illustrated, the base or foot portions 168' are shown as formed by extending the flanges 164 on the adjacent ends of the trough sections.

Referring now to Figures 29 to 35, Figure 29 illustrates a conveyer apparatus comprising a series of U-shaped trough sections 180 and making use of combination hanger and coupling structures shown in greater detail in Figures 30 and 31.

Here the flanges 181 at the ends of the trough sections are bolted directly together, as indicated at 182, and are formed with integral supporting base or foot portions 183. The upper ends of one of the flanges 181 at each trough joint are cut away and fitted with offset plates 184, thereby providing pockets 185 for seating the opposite ends of a crossbar 186 forming a part of the hanger structure, the ends of said crossbar having holes 187 for bolting the same in place by means of a pair of bolts 182. The hanger structure proper comprises a substantially triangular frame 188, the bottom of which cradles the split bearing elements 189 for the conveyer shaft coupling 14 and is provided with a removable retaining yoke 190 secured to the sides of the frame 188 by bolts 191. The horizontal top portion of said frame 188 is also provided with bolt openings 192 and nuts 192' welded in place for wing bolts 193 which secure the hanger structure to the top cover plate 194 of the U-shaped conveyer trough.

The upper edges of the trough sections 180 are formed with outwardly projecting flanges 195 which are connected with the outer edges of the cover plate 194 by bolts 196—a dust seal structure being formed by the use of channel strips 198 embracing said flanges and outer edges of the cover 194, and a felt strip 199 being interposed (in some conditions) between said flanges and the cover, as illustrated in Figures 30 and 35. At each of the joints between trough sections, said channel pieces are connected by a cross cover strip 198' for overlying the hanger structure, said cover strip 198' being secured in place by means of the bolts 193 (see Figure 35).

In Figures 33 and 34 is illustrated a similar but modified form of the same type of construction designed to be clamped between the meeting ends of adjacent trough sections. This is accomplished by forming the triangular hanger frame 188, not as a part of a crossbar 186 as in Figure 32, but as a part of or rigid with a plate member 200 following the cross-sectional contour of the trough, and providing said member with bolt holes 201 for adapting it to be clamped in place

between the end flanges 181 of the trough sections 180, as clearly illustrated in Figure 33. The remaining features of this type of the construction are identical with that already described and illustrated in Figures 30 and 31.

In such forms of construction it is important to point out that the flanges on the ends of the trough sections serve as master flanges for not only supporting the conveyer trough but also insuring positive and accurate alinement of the bearings as well as a firm support therefor, to eliminate vibration or any weaving tendency of the relatively light gauge of trough or casing. Moreover the recesses provided for the mounting of the hanger structure insure correct location without any measuring or fitting, and without the drilling of any additional holes for bolting the parts in place.

So far as the various types of construction are concerned, these are primarily illustrative of the fundamental purpose of the invention, which is to provide an improved construction in which the hanger bearings themselves will always be located at the joints or connection points between the sections of the conveyer trough or housing, thereby resulting in a coupling and hanger construction which is of a very much stronger type than in prior types not adhering to such a principle of combining all these structural features in a single unit. In addition to greatly strengthening the structure, there also results the immense advantage as regards increasing the simplicity and speed of repair operations, which is brought about by a principle or standard of construction in which, in most of the illustrated types herein, the combined length of the conveyer section and one of its hanger bearings is made to match a section of the conveyer trough and its coupling member. It is believed that such an important feature or standard of construction is novel in spiral or screw conveyer apparatus comprising multiple sections which necessitate coupling and hanger structures at several spaced points throughout the length of the apparatus, and that the improved results flowing from such a novel construction are of a correspondingly outstanding character. Not the least important of such improved results or advantages of the invention is the insuring of the accurate and correct alinement of the parts at the joints, as well as the provision for effective resistance of torque in several of the designs or types of construction shown, all of which is of course of vital importance for eliminating power losses, keeping down premature wear, and hence reducing the frequency of maintenance operations.

As is evident from the foregoing, these improvements have been adapted for the various types of trough construction, such as already mentioned, including cylindrical (either of the split or non-split type) and the U-shaped type of conveyer trough. While the invention is not to be confined to closed-trough construction, the drawings have been made with a view to the importance of the invention with reference to the cylindrical form of trough, because of its directly lending itself to the use of water or steam jacketing means, for either heating or cooling the material in transit, for it is apparent that a suitable jacket structure may readily be constructed and applied as an envelope enclosing the trough in suitably spaced relation thereto, together with connections for the inlet

and outlet of a heating or cooling medium to the jacket space.

It is also of importance to point out that the present improved dust-seal construction of the closed trough type is effective for reducing the likelihood of fire and dust explosions occurring in grain elevators, various processing industries and other plant operations.

A special advantage of the round or cylindrical trough type of conveyer is the wear-compensating feature of such trough design, which enables the same to be turned for the purpose of replacing the worn bottom sections of the trough with the upper trough sections which of course are subject to relatively little wear—thus practically doubling the useful life of each trough section or unit of the conveyer.

While we have illustrated and described various forms and arrangements of coupling and hanger units adapted to carry out the several important purposes of our invention, it is to be understood that these do not represent all the different arrangements or modifications which may be adopted for incorporating the essential features constituting the improvements which we regard as our invention, but that various other modifications or adaptations may be followed which nevertheless appropriate the essential feature and principle of our improvements. We therefore desire to be understood as expressly reserving the right to make such changes or modifications as may be deemed to fairly fall within the spirit and scope of our invention as defined by the appended claims.

What we claim and desire to secure by Letters Patent is:

1. Screw conveyer apparatus comprising multiple trough sections, a screw propelling section for each trough section, and separate and independent assembly units providing a coupling structure for adjoining ends of the trough sections and also bearing means for adjoining ends of the screw propelling sections, said units being removable and replaceable by direct transverse movement into and out of the space between adjoining ends of the trough sections and the length of each trough section and coupling structure matching the length of the corresponding screw propelling section and its bearing means.

2. In screw conveyer apparatus, the combination of multiple conveyer trough sections, screw propelling sections, and coupling units removably connecting the adjoining ends of the trough sections and having bearing means for adjoining ends of said screw propelling sections, said coupling units being removable and replaceable by direct transverse movement into and out of the space between adjoining ends of said trough sections.

3. In screw conveyer apparatus, the combination of multiple conveyer trough sections, screw propelling sections, having telescoping shaft couplings between adjoining sections thereof, and coupling means removably connecting the adjoining ends of the trough sections and provided with bearings for said shaft couplings between the screw propelling sections.

4. Screw conveyer apparatus comprising a sectional conveyer trough, a screw propelling section for each section of the trough, and removable coupling means for adjoining ends of the several trough sections and having split bearing means for the corresponding joints between the screw propelling sections, said coupling means being removable and replaceable by direct trans-

verse movement into and out of the space between adjoining ends of the trough sections.

5. Screw conveyer apparatus comprising a sectional conveyer trough, a screw propelling section for each trough section, and split coupling units removably connecting adjoining ends of the several trough sections and providing bearing means for the corresponding joints between the screw propelling sections.

6. In screw conveyer apparatus, the combination of conveyer trough sections, a screw propelling section for each of the trough sections, and a split coupler unit connecting adjoining ends of said trough sections and having a split bearing for adjoining ends of corresponding screw propelling sections.

7. Screw conveyer apparatus comprising conveyer trough sections, a screw propelling section for each of said trough sections, and supporting means comprising a base portion and coupling means removably connecting the adjoining ends of said trough sections, together with bearing means for the adjoining ends of said screw propelling sections, said supporting means being removable and replaceable by direct transverse movement into and out of the space between adjoining ends of the trough sections.

8. Screw conveyer apparatus comprising aligned conveyer trough sections, a screw propelling section for each of said trough sections, and a split coupler unit connecting the adjoining ends of said trough sections, one section of said coupler unit having a supporting base portion and the other section of said unit having bearing means for adjoining ends of said screw propelling sections.

9. Screw conveyer apparatus comprising a sectional conveyer trough made up of separable split units, a screw propelling section for each of said trough units, a split coupling unit removably connecting adjoining ends of said trough units, and bearing means carried by one portion of the coupling unit for the adjoining ends of said screw propelling sections.

10. Screw conveyer apparatus comprising a longitudinal series of conveyer trough units made up of split casings separably connected and having a screw propelling section enclosed by each of said units, correspondingly split coupling units removably connecting the adjoining ends of said trough units, and split bearing means carried by said coupling units for the adjoining ends of the screw propelling sections.

11. Screw conveyer apparatus comprising a longitudinal series of split conveyer trough units, a screw propelling section enclosed by each of said trough units, correspondingly split coupling units removably connecting the ends of said trough units, and split bearing structures carried by the respective portions of said coupling units for the adjoining ends of said screw propelling sections.

12. A combination coupling and hanger construction for sectional screw conveyer apparatus comprising a coupling member having means of attachment to adjoining ends of conveyer trough sections, said coupling member being removable and replaceable by direct transverse movement into and out of the space between adjoining ends

of the trough sections, and a hanger structure supported by said coupling member and provided with bearing means for adjoining ends of the interior conveyer mechanism.

13. A combination coupling and hanger construction for sectional conveyer apparatus comprising a split or sectional coupling member having means of attachment to adjoining ends of conveyer trough sections, and a hanger structure comprising bearing elements carried by respective portions of the coupling member and cooperating to journal the coupled ends of the interior conveyer mechanism.

14. A combination coupling and hanger construction for sectional conveyer apparatus, comprising a coupling member having flanges for connection to the adjoining ends of conveyer trough sections and removable and replaceable by direct transverse movement into and out of the space between adjoining ends of the trough sections, and a hanger structure supported by said coupling member and provided with bearing means for journaling the coupled ends of the interior conveyer mechanism.

15. A combination coupling and hanger construction for sectional conveyer apparatus, comprising a coupling member having means of attachment to adjoining ends of conveyer trough sections and removable and replaceable by direct transverse movement into and out of the space between adjoining ends of the trough sections, and an interior hanger structure carried by said coupling member and provided with bearing means for journaling the coupled ends of the interior conveyer mechanism, said hanger structure being offset from the central vertical plane of the conveyer for streamlining the flow of material therethrough.

16. Screw conveyer apparatus comprising multiple and separable assemblies or units of conveyer trough sections enclosing sectional screw propelling mechanism, and separate and independent assembly units providing trough coupling and hanger bearing structures for the adjoining ends of the sections of said conveyer trough and screw propelling mechanism respectively, said independent units having transverse projecting portions, and the adjoining ends of said trough units having connecting portions formed with pockets for receiving and seating said projecting portions.

17. Screw conveyer apparatus comprising multiple and separable assemblies or units of conveyer trough sections formed with transverse flanges and enclosing correspondingly matching sections of screw propelling mechanism, separate and independent assembly units providing trough coupling and hanger bearing structures for corresponding adjoining ends of the sections of said conveyer trough and screw propelling mechanism respectively, said independent assembly units having connecting portions coextensive with the flanges of said trough sections, and common fastening means for securing together the connecting portions and flanges of both said independent units and adjoining trough sections.
